UNITED STATES PATENT OFFICE.

BURDETTE S. BOONE, OF PAXTON, ILLINOIS.

VENTILATOR ATTACHMENT.

No. 900,349.

Specification of Letters Patent.

Patented Oct. 6, 1908.

Application filed November 11, 1907. Serial No. 401,694.

To all whom it may concern:

Be it known that I, BURDETTE S. BOONE, a citizen of the United States, residing at Paxton, in the county of Ford and State of Illinois, have invented a new and useful Ventilator Attachment, of which the following is a specification.

This invention relates to ventilating attachments for windows of that character described to be used in connection with a partly raised sash.

The object of the invention is to provide an attachment of this character capable of being adjusted to fit window casings of different widths, the attachment being so constructed as to offer practically no hindrance to the passage of light rays while the ventilator is in place.

Another object is to provide novel connections between the various portions of the ventilator.

With these and other objects in view the invention consists of certain novel features of construction and combinations of parts which will be hereinafter more fully described and pointed out in the claims.

In the accompanying drawings is shown the preferred form of the invention.

In said drawings: Figure 1 is a perspective view of a ventilator constructed in accordance with the present invention. Fig. 2 is a section therethrough showing the same in position within a window casing. Fig. 3 is a detail view showing a modified form of extension.

Referring to the figures by characters of reference, 1 designates an elongated preferably rectangular strip of diaphanous material, preferably glass, and upon each end portion of this strip is arranged a slide 2 preferably formed of thin sheet metal and having its upper and lower edge portions extending at right angles from one face thereof as indicated at 3 and provided with inwardly extending alining retaining flanges 4, these flanges, and the body portion of the slide forming channels 5 in which the edge portions of strip 1 are designed to fit. An extension 6 projects from one end of the slide 2 and preferably at right angles thereto and this extension has one or more openings 7 therein for the reception of screws or other suitable fastening means.

In using the device herein described the

slides 2 are shifted longitudinally upon the strip 1 until the extensions 6 are brought into contact with opposite faces of a window casing. They are then secured therein by means of screws or other devices inserted through the openings 7 and when so positioned the strip 1 will extend throughout the width of the casing and directly in front of the path of the sash, which has been indicated at 8 so that an air space 9 is formed between said strip and the sash. By raising the sash so that its lower edge assumes a position adjacent but below the upper edge of the body 1 air is free to enter the room by passing under the sash and upward and over the strip 1. The passage of light under the sash 8 will not be hindered because practically the entire ventilating attachment is formed of a transparent material.

In order that the ventilator may be readily detached the extension 6 may, if desired, be provided with inwardly and upwardly extending L-shaped slots 10 designed to engage retaining screws or buttons fastened to the inner or adjoining face of the window casing. By slotting the extensions in this manner it is possible, by raising the attachment and pulling it outward, to withdraw the extensions from engagement with the retaining means. After said retaining means have been once placed in position the ventilator can be readily mounted thereon at any time without the necessity of using any tools.

It will be seen that the device is very simple, durable and efficient, can be readily applied, and is doubly desirable as a ventilator because it does not tend to darken the room in which the window is located by obstructing any light rays.

What is claimed is:

1. A ventilator attachment comprising an elongated diaphanous body strip, a slide embracing and adjustably mounted upon each end of the strip, each slide having oppositely disposed channels for the reception of opposite edge portions of the strip, an extension upon each slide, and inwardly and upwardly extending slots within each extension for detachably engaging retaining means upon a window casing.
2. The combination with a window casing and headed fastening devices extending from opposite faces thereof; of a ventilator

comprising a panel, slides embracing and
movably mounted upon the end portions of
the panel, and an extension upon each slide,
each extension having L-shaped slots ex-
5 tending inwardly and upwardly thereinto
for the reception of the fastening devices.

In testimony that I claim the foregoing as

my own, I have hereto affixed my signature
in the presence of two witnesses.

BURDETTE S. BOONE.
